UNITED STATES PATENT OFFICE.

MORTIMER A. HOWE, OF TACOMA, WASHINGTON.

SEPARABLE DOUBLE LETTER-SHEET.

No. 858,001.

Specification of Letters Patent.

Patented June 25, 1907.

Application filed February 7, 1905. Serial No. 244,548.

To all whom it may concern:

Be it known that I, MORTIMER A. HOWE, a citizen of the United States, residing at Tacoma, in the county of Pierce and State of Washington, have invented new and useful Improvements in Separable Double Letter-Sheets, of which the following is a specification.

My invention relates to devices for producing and preserving manifold copies of letters and manifold copies of the replies thereto, and has for its objects the providing of a separable double letter sheet having four flat surfaces after folding, one of which is to be used in writing a letter and the surface directly underneath and facing the same way is to be used to receive and hold a carbon copy of the letter written, one of the two remaining surfaces is designed to furnish space upon which to reply to the letter above mentioned and the surface directly underneath the surface on which the reply is written, and facing the same way is designed to receive and hold a carbon copy of the reply, and to provide a single leaf to be inserted between the leaves of the separable, double letter sheet which single leaf is designed to receive and hold a carbon copy of the letter; said copy to be temporarily retained as an office record until the reply to the letter is received.

Heretofore in keeping a record of letters and the replies thereto, it has been the custom to make an impression of the letter written upon a leaf in a bound book. This method is slow and unsatisfactory in that, copies of the letter and the reply thereto are in separate places and valuable time is lost in bringing the two together when reference is wanted and for many other reasons too numerous to mention. With my invention these troubles are eliminated: when a reply is received it is only necessary to turn the leaf over and read the record of the original letter.

Certain other minor details are also embodied in my improved construction as will be hereinafter more definitely pointed out and explained, reference being had to the accompanying drawings, in which:

Figure 1 is a plan view of my improved, separable, double letter sheet showing the two leaves before being folded together. Fig. 2 is a perspective view after the leaves have been folded showing the carbon sheet inserted and ready for writing the letter and

copying the same onto the inner surface of the second leaf of the letter sheet, also showing the single leaf and carbon sheet inserted and ready to receive a copy of the letter. Fig. 3 is a perspective view after the leaves have been folded and the letter written, as referred to in the description of Fig. 2, and showing a carbon sheet inserted ready for writing the reply to the above mentioned letter and making a carbon copy of the reply on the inner surface of the first leaf.

Similar letters refer to similar parts in the several views.

A represents that surface of the first leaf upon which the original letter is written, B represents that surface of the second leaf upon which a carbon copy of the original letter is made, C represents that surface of the second leaf upon which the reply to the original letter is written, D represents that surface of the first leaf upon which a carbon copy of the reply is made, E represents the carbon sheets used in making the carbon copies above referred to, F represents the line at which the leaves are folded together and at or near which they are afterward separated, G represents the single leaf or temporary office copy of the letter and H represents the carbon sheet used in making the carbon copy on the single leaf.

The uses to which my invention may be put and the manner of using the same are as follows: A. B. C. or any person or company wishing to write a letter to a second person or company inserts two carbon sheets E and H, and a single sheet G between the two leaves of the letter sheet, (see Fig. 2) the copying surface of the carbon sheet E facing the surface B and the copying surface of the carbon sheet H facing the single sheet G, the letter is then written upon the surface A and copied onto the surfaces B and G, the carbon sheets E and H and the single sheet G are then removed and the double letter sheet is then despatched to the person or company to whom the letter is written, the single sheet G being kept as a temporary record pending the receipt of the reply to the letter. Upon receipt of the letter sheet the person or company to whom it is written inserts a carbon sheet E, (see Fig. 3) the copying surface of the carbon sheet E facing the surface D, the person or company then writes a reply to the letter upon the surface C and the reply is copied onto the surface D, the carbon sheet E is then removed and the two leaves sep-

arated at or near the line F and one of the leaves returned to the writer of the original letter, and the other leaf retained by the person or company replying to the letter.

5 It is obvious that the line F may be perforated or formed by lines of weakness, or formed by gluing two sheets together, or formed by merely folding the two leaves together and that it may be placed at any or 10 all of the four edges of the leaves. It is also obvious that it may not at all times be necessary to print the letter head or the preamble to the reply thereto but blank sheets may be used instead. It is also obvious that it may 15 not at all times be necessary to use the single sheet G, as in some cases it may not be needed. I also reserve the right to apply this method of construction and use to note heads, memorandum heads and other papers 20 to which replies are to be received; in substantially the same manner as described regarding letters and the replies thereto.

Having described my invention, what I claim as new and desire to secure by Letters 25 Patent is:

1. As an improved article of manufacture, a letter sheet folded at its middle comprising two separable parts joined by a weakened line and one of said parts having printed on 30 the outer face thereof a letter head and having written on the outer face thereof a letter and having written on the inner face thereof a carbon copy of the reply to said letter and the other part having printed on the outer 35 face thereof the name of the party sending

the original letter and the commencement of a reply thereto and having written on the outer face thereof a reply to the original letter and having written on the inner face thereof a carbon copy of the original letter, 40 substantially as described.

2. As an improved article of manufacture, a combination record, letter and reply set consisting of two parts, one of said parts being a single leaf, and the other part consisting of two separable leaves, folded together and joined by a weakened line and the two leaves so folded being interleaved with the single leaf, and the outer surface of the first leaf of the double part being printed with a 45 letter head and having a blank space, and the inner surface of the second leaf of the double part having a blank space, and the outer surface of the second leaf of the double part being printed with the name and address of the person whose letter head is on the first leaf and being printed with a preamble to the reply to a letter, and having a blank space, and the inner surface of the first leaf of the double part having a blank space 50 and the whole being interleaved with carbon sheets, substantially as described and for the uses and purposes as set forth.

I hereunto affix my signature to the foregoing specifications in the presence of two 55 subscribing witnesses.

MORTIMER A. HOWE.
